(57) **CLAIM**

We claim the ornamental design for the leash anchor and container support, as shown and described.

DESCRIPTION

FIG. 1 is a perspective view of the leash anchor and container support according to our design;

FIG. 2 is a front elevational view of the leash anchor and container support according to our design;

FIG. 3 is a rear elevational view of the leash anchor and container support according to our design;

FIG. 4 is one side elevational view of the leash anchor and container support according to our design;

FIG. 5 is the other side elevational view of the leash anchor and container support according to our design;

FIG. 6 is a top plan view of the leash anchor and container support according to our design; and,

FIG. 7 is a bottom plan view of the leash anchor and container support according to our design.

The broken line showing is for illustrative purposes only and forms no part of the claimed design.
